UNITED STATES PATENT OFFICE.

JONATHAN RUSSELL, OF PHILADELPHIA, PENNSYLVANIA.

ARTIFICIAL LEG.

Specification of Letters Patent No. 9,202, dated August 17, 1852.

To all whom it may concern:

Be it known that I, JONATHAN RUSSELL, of the city and county of Philadelphia and State of Pennsylvania, have invented certain new and useful Improvements in Artificial Legs; and I do hereby declare the following to be a full, clear, and exact description of the same, reference being had to the accompanying drawings, making a part thereof, in which—

Figure 1 represents a view of an artificial leg to be attached above the knee; and Fig. 2, represents a similar view with one half of the shell cut away so as to exhibit the interior parts.

Similar letters in both the figures denote the same parts.

The nature of my invention consists in so combining and arranging the several parts of an artificial leg, as that the knee-joint shall be firmly locked by the weight upon it, when applied to either the toe, or heel part of the foot, thus making the knee-joint perfectly rigid when the leg is erect and the weight of the body or a portion of it, is thrown upon it, at the will of the wearer.

To enable others skilled in the art to make and use my invention, I will proceed to describe the same with reference to the drawings.

The leg may be constructed of wood, or any other well known equally light and strong material, and when it is to be united to the natural limb above the knee, should be made in four distinct pieces, so as to form joints at the knee, ankle, and ball or toe of the foot, and these joints may be covered with any elastic material, so that the exterior of the leg will present a smooth, uniform surface. When the artificial leg is joined to the natural limb below the knee the same lock joints may be used, and if deemed necessary or essential to a better control of the part, it may be made to lock into the thigh bandages.

A, represents the top part of the artificial leg, which is hollowed out, forming as it were a socket, for that portion of the natural limb, which rests in it upon a pad or otherwise.

B, represents the portion between the knee and the ankle, the top of which is rounded off, so that the lower end of the top part A, will fit over it, forming a cup-joint. There is a tenon C, on the part A, which fits into

an open mortise or slot in the part B, so that the joint shall be perfectly rigid laterally, and move only in the direction of a natural knee joint—the two parts being connected by a bolt or pin D, upon which the part A, 60 may swing. A shoulder E, is formed upon the part B, against which, when the knee-joint is bent its utmost, the portion F, of the upper part A rests, keeping the parts from moving too far, and straining unnecessarily the inner parts. The joint at the ankle, may be made in a manner similar to that of the knee-joint, as represented by the tenon or tongue G, and pin H, and as the motion of the ankle is naturally much less than that at the knee, and must be in a direction both forward and back, I form the shoulder as seen at I I, to allow of this extent of motion. The toe-part has a tenon or tongue J, extending back into the foot, 70 and is secured by a pin K, on which it works, the joint or shoulders of the joint or both, being rounded off for the purpose. The interior of the part B, is left open, or cut away, to receive a helical spring L, to the 80 upper end of which is attached a gut or other strong cord a, which passes over a friction roller b, and thence past the pin D, in which there is a notch d cut (as seen in Fig. 2) to prevent it from being too much strained when the knee-joint is bent its utmost—thence to a thumb screw c, by which the spring L, and the cords &c. attached to it, may be adjusted to any desired tension. On a small shaft e, on which the friction 85 roller b, is placed, is also arranged a bent lever f, to the lower end of which is affixed a rod g, which is attached to the lower end of the spring L. The bent arm of the lever f, has a projection or tooth h, upon it, which, when the spring is drawn down by either of the cords i, j, which pass down over a friction roller k,—(one of which i is fastened to the toe part of the foot, and the other j, to the instep), draws the tooth h, in the arm of the lever f, into a notch or recess l, cut in the tenon of the part A, and firmly locks the knee-joint, in which position it will remain, until the pressure of the body is thrown from the heel or toe, as the case may be, and which operates the cords i, j, onto the ball of the foot, when the contraction of the spring will draw out the tooth h, leaving the knee-joint free to move again.

It will be perceived that all the motions 110

of the leg and joints are controlled by the one spring L, it being the only spring used, which makes the leg extremely simple, without any liability of becoming deranged, and 5 it may be used for straightening out, or aid in so doing, the lower part of the leg, when the person rises from a sitting posture, so that the artificial leg will be in the proper position for supporting the body, or for 10 stepping forward, as the case may be.

In walking it is very desirable that the knee joint should be at all times perfectly under the control of the wearer, and particularly when the artificial limb is at its 15 greatest inclination with the body, which is on the first or last of each step, and in which case the whole weight is upon the heel or the toe parts of the foot. By my arrangement the weight coming upon the heel or toe 20 either, locks the joint, and forms a perfectly reliable support, at the will of the wearer,

until the weight is thrown upon the ball of the foot.

Beside the advantages, of extreme simplicity, and permanency in my invention, is 25 that of cheapness, being able to furnish the leg complete, at a cost almost, if not quite fifty per cent. less than those now in use.

Having thus fully described my invention what I claim therein as new, and desire 30 to secure by Letters Patent, is—

So operating the lever f, through the spring L, by means of the cords i, j, which are respectively attached to, and operated by, the toe and heel part of the foot, as that 35 when the leg is bent forward or back on the ankle joint, the knee joint shall be locked by said lever, substantially as described.

JONATHAN RUSSELL.
